Patented Dec. 29, 1970

219,592

TELEVISION OR RADIO RECEIVING ANTENNA

Christopher Owen Gibbons, 495 East 1350 North,
Bountiful, Utah 84010

Filed Sept. 2, 1969, Ser. No. 19,021

Term of patent 14 years

Int. Cl. D14—03

U.S. Cl. D26—14

FIG. 1

FIG. 2

FIG. 3

FIG. 1 is a perspective view of a television or radio receiving antenna showing my new design;

FIG. 2 is a top plan view of the antenna; and
FIG. 3 is a bottom plan view of the antenna.

I claim:

The ornamental design for a television or radio receiving antenna, substantially as shown and described.
